BATHTUB AND CABINET THEREFOR

Ernest E. Jellison, Twin Falls, Idaho

Application February 28, 1933, Serial No. 659,009

3 Claims. (Cl. 4—186)

The present invention relates to the combination of a cabinet and a bathtub housed therein for use in such houses as do not have proper bathing facilities.

5 The object of the invention resides in the provision of a bathing outfit of this nature which is simple in its construction, compact and convenient in its arrangement of parts, easy to manipulate, thoroughly efficient and reliable in use and otherwise well adapted to the purpose for which it is designed.

With the above and numerous other objects in view as will appear as the description proceeds, the invention consists in certain novel features 15 of construction, and in the combination and arrangement of parts as will be hereinafter more fully described and claimed.

In the drawings:

Figure 1 is a vertical longitudinal section 20 through the outfit showing the cabinet closed.

Figure 2 is a similar section showing the cabinet open.

Figure 3 is a top plan view thereof with the cabinet open.

25 Figure 4 is a vertical transverse section taken substantially on the line 4—4 of Figure 1.

Figure 5 is a vertical transverse section taken substantially on the line 5—5 of Figure 1.

Figure 6 is a vertical transverse section taken 30 substantially on the line 6—6 of Figure 2.

Figure 7 is a top plan view of the water supply reservoir.

Figure 8 is a horizontal section therethrough, and

35 Figure 9 is a perspective view of the waste water tray.

Referring to the drawings in detail it will be seen that the cabinet comprises a rectangular bottom 5 with end walls 6 rising therefrom and 40 side walls 7 rising therefrom. A lid 8 is hingedly mounted on one of the side walls 7 for closing the cabinet. The other side wall is provided with an opening through which is slidably a waste water receiving tray 9 which is in the form of a drawer and has a bail 10 pivotally connected therewith as at 11 and half of the tray has a fixed cover 12. This tray slides between guides 14 rising slightly from the cabinet 5. Casters 15 support the bottom and there is one caster located adjacent each corner thereof. Slots 16 in 45 the ends of the bottom 5 are provided for the movement of legs therethrough. The legs are arranged in pairs, each pair including an elongated leg 17 pivotally mounted on a bracket 18 and a leg 19 pivotally mounted on a bracket 20,

these brackets being fixed to the bottom 5. A pin and slot connection 21 is provided between the legs. The free ends of the legs are curved outwardly and downwardly as indicated to advantage in Figures 4 and 6. Springs 22 are connected with the legs 17 for normally holding them in retracted position shown in Figure 4. Cables 23 are connected with the legs 17 and with the lid 8 and when the lid 8 is swung to open position these cables are caused to pull upon the legs 17 thereby swinging the legs 17 and 19 to floor engaging position as shown in Figure 6, thereby preventing the movement of the cabinet while the lid is open. A brace arm 25 is pivotally engaged on one end wall so that it may be swung up to the position shown in Figure 6 for engaging an abutment 26 provided on the lid to hold the lid in open position. When the lid is closed, of course, the springs 22 return the legs to retracted position.

Cleats 27 are provided on the inner surfaces of the walls 6 and 7 adjacent the upper edges thereof and flanges of a tub 28 rest thereon. The bottom 29 of this tub slopes from one end to the other and the deeper end is disposed over the tray 9 and a drain pipe 30 leads therefrom and is valved as at 31 so that when the valve is open water in the tub will drain into the tray 9. A supply reservoir is denoted by the numeral 33 and includes two compartments 34 separated by partitions 35 which are spaced from each other to provide air insulation between the two compartments. Drain spouts 36 are swivelly mounted on the end walls of the compartments in communication therewith and of course when in upright position these pipes prevent the flow of the water from the reservoir but when swung down to the position shown in Figure 2 the water is free to flow into the tub. One compartment is used for hot water and the other for cold water. This reservoir is hingedly mounted as at 37 so that it may be disposed in the position shown in Figure 1 when the lid 8 is in closed position and may be swung to the position shown in Figure 2 when it is in open position. Foldable legs 38 are provided for the reservoir to support it in the outer position. A suitable storage casing 40 is provided on the bottom 5 under the shallow portion of the tub.

From the above detailed description it will be seen that I have devised a bathtub housed in a cabinet so that it may be stored in any room of the house for ready use when desired.

It is thought that the construction, operation, utility and advantages of this invention will now

be clearly understood without a more detailed description thereof.

The present embodiment of the invention has been described in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. In combination, a bath-tub cabinet, casters supporting the cabinet, legs arranged in pairs, means for pivotally mounting the legs of each pair, 20 and the legs of each pair having pin and slot connections with each other and ends curved to extend through slots provided in the bottom of the cabinet, springs associated with the legs to normally hold the same retracted, a hinged lid 25 for the cabinet, and means connecting the hinged lid with the legs so that when the lid is swung to open position said legs are extended to floor engaging position.

2. In combination, a bath-tub cabinet, casters supporting the cabinet, legs arranged in pairs,

means for pivotally mounting the legs of each pair, and the legs of each pair having pin and slot

connections with each other and ends curved to extend through slots provided in the bottom of the cabinet, springs associated with the legs to

normally hold the same retracted, a hinged lid for the cabinet, and means connecting the hinged lid with the legs so that when the lid is swung to open position said legs are extended to floor

engaging position.

3. In combination, a bath-tub cabinet, casters supporting the cabinet, legs arranged in pairs,

means for pivotally mounting the legs of each pair, and the legs of each pair having pin and slot

connections with each other and ends curved to extend through slots provided in the bottom of the cabinet, springs associated with the legs to

normally hold the same retracted, a hinged lid for the cabinet, and means connecting the hinged lid with the legs so that when the lid is swung to open position said legs are extended to floor

engaging position.

4. In combination, a bath-tub cabinet, casters supporting the cabinet, legs arranged in pairs,

means for pivotally mounting the legs of each pair, and the legs of each pair having pin and slot

connections with each other and ends curved to extend through slots provided in the bottom of the cabinet, springs associated with the legs to

normally hold the same retracted, a hinged lid for the cabinet, and means connecting the hinged lid with the legs so that when the lid is swung to open position said legs are extended to floor

engaging position.

5. In combination, a bath-tub cabinet, casters supporting the cabinet, legs arranged in pairs,

means for pivotally mounting the legs of each pair, and the legs of each pair having pin and slot

connections with each other and ends curved to extend through slots provided in the bottom of the cabinet, springs associated with the legs to

normally hold the same retracted, a hinged lid for the cabinet, and means connecting the hinged lid with the legs so that when the lid is swung to open position said legs are extended to floor

engaging position.

6. In combination, a bath-tub cabinet, casters supporting the cabinet, legs arranged in pairs,

means for pivotally mounting the legs of each pair, and the legs of each pair having pin and slot

connections with each other and ends curved to extend through slots provided in the bottom of the cabinet, springs associated with the legs to

normally hold the same retracted, a hinged lid for the cabinet, and means connecting the hinged lid with the legs so that when the lid is swung to open position said legs are extended to floor

engaging position.

7. In combination, a bath-tub cabinet, casters supporting the cabinet, legs arranged in pairs,

means for pivotally mounting the legs of each pair, and the legs of each pair having pin and slot

connections with each other and ends curved to extend through slots provided in the bottom of the cabinet, springs associated with the legs to

normally hold the same retracted, a hinged lid for the cabinet, and means connecting the hinged lid with the legs so that when the lid is swung to open position said legs are extended to floor

engaging position.

2. In a device of the character described, a cabinet, casters supporting the cabinet, said cabinet having a bottom wall provided adjacent each end with slots, a pair of legs pivotally mounted within the cabinet adjacent each end thereof, said legs having ends movable through the slots for engaging the ground, a hinged lid for the cabinet, and operating connections between said lid and the legs for projecting the said ends of the legs through the slots into ground engaging position when the lid is swung to an open position, and for retracting said legs when the lid is swung to a closed position.

3. As a new article of furniture, a cabinet, a bathtub arranged in the cabinet, a reservoir hinged to one wall of the cabinet and swingable into the tub for storage purposes; said reservoir provided with hot and cold water compartments, and drain spouts swivelly mounted on the reservoir, there being one drain spout for each of said compartments and adapted to be disposed in one position to prevent the flow of water from the reservoir, and in a second position for draining the water from a compartment into the tub.
